UNITED STATES PATENT OFFICE.

JOSEPH FIALA, OF NEW YORK, N. Y., ASSIGNOR TO STANDARD PNEUMATIC ACTION COMPANY, OF NEW YORK, N. Y., A CORPORATION OF NEW YORK.

EXPRESSION DEVICE FOR AUTOMATIC MUSICAL INSTRUMENTS.

1,178,004.

Specification of Letters Patent.

Patented Apr. 4, 1916.

Application filed December 7, 1915. Serial No. 65,618.

To all whom it may concern:

Be it known that I, JOSEPH FIALA, a citizen of the United States, residing at New York, in the county of New York and State 5 of New York, have invented a new and useful Expression Device for Automatic Musical Instruments, of which the following is a specification.

This invention relates to an expression 10 device for automatic musical instruments and is more particularly designed for use in connection with player pianos and piano players. In these types of instruments the operating mechanism commonly comprises 15 a large number of pneumatic devices, each one of which controls a separate note in the instrument. These pneumatics are usually operated upon the suction or exhaust principle, the low pressure of the exhaust being 20 produced by foot-operated bellows. In order to prevent frequent changes of pressure due to irregular operation of the bellows, a storage reservoir is commonly provided which acts as a pneumatic governor 25 for absorbing the irregularities of pressure. In the playing of the instrument it is frequently desirable to accentuate a given note or series of notes by more vigorous operation of the pumping pedals. The storage 30 reservoir or pneumatic governor however tends to neutralize the effect of the increased speed of operation of the pedals and it thus becomes desirable under these conditions to temporarily shut off the storage reservoir 35 from the wind trunk. Various devices have been heretofore constructed for accomplishing this purpose, and it is the object of my present invention to improve and simplify the construction of such devices, making 40 them more efficient in operation and more readily adjustable to varying conditions.

With this general object in view my invention relates to certain arrangements and combinations of parts which will be hereinafter described and more particularly pointed out in the appended claim.

A preferred form of my invention is shown in the drawings in which—

Figure 1 is a vertical sectional elevation 50 of a storage reservoir having my improved expression device applied thereto, the section being taken on the line 1—1 in Fig. 2,

and Fig. 2 is a diagrammatic plan view showing the general relation of the storage reservoir to the pneumatic system of the instrument.

Referring to the drawings, the main wind trunk is indicated at 10. At one end the wind trunk is connected to a pipe 11 leading to the pneumatic actions of the instrument 60 and at the opposite end it is connected to pumps or bellows 12 by which the air in the wind trunk and actions may be exhausted.

The storage reservoir 13 is connected to the wind trunk at a point intermediate its 65 ends. The reservoir is constructed in the form of a collapsible bellows having a fixed leaf 14 firmly secured to the wind trunk 10 and having a movable leaf 15 hinged to the fixed leaf. The leaves 14 and 15 are normally forced apart by a spring 16 positioned within the bellows. The reservoir 13 is connected to the wind trunk 10 by a transverse passage 17, the reservoir being otherwise 75 closed.

An expression valve 18 is hinged at 19 to the leaf 14 and when closed covers the passage 17. A threaded plunger 20 is mounted to slide transversely through the fixed wall 14 and is provided at its inner end with a 80 head 21 engaging an extension 22 upon the valve 18. A nut 23 is threaded upon the plunger 20 and is engaged by the free end of a spring 24 secured at 25 to the leaf 14.

The spring 24 normally presses the plunger 20 inward until the nut 23 engages the outer face of the wall 14, the plunger being thus made effective to position the valve 18 as shown in Fig. 1. The amount of valve opening may be regulated by turning the nut 90 23 upon the threaded plunger 20 and the tension of the spring 24 may be adjusted by means of a screw 26 which engages the spring 24 intermediate its ends.

A stop screw 27 may also be provided for 95 limiting the rearward movement of the valve 18. Accurate adjustment of the stop 27 is not commonly necessary as the weight of the valve 18 will cause it to remain in contact with the head 21 of the plunger 20 100 even if it does not engage the stop 27. The stop may be adjusted, however, by removing the plate 28 provided upon the hinged leaf 15 of the storage reservoir.

Having thus described my invention, the operation thereof will be evident to those skilled in the art. Under normal conditions the valve 18 will remain open as shown in Fig. 1 and air will flow freely in one direction or the other through the passage 17 to equalize the pressure in the wind trunk 10.

When the foot-operated bellows are suddenly operated at increased speed, thereby producing an abrupt drop of pressure in the wind trunk 10, the excess of pressure in the storage reservoir will cause the valve 18 to close, overcoming the resistance of the spring 24. As soon as this valve is closed the storage reservoir 15 is cut off entirely from the pneumatic system and variations in pressure in the wind trunk will be transmitted direct to the pneumatic actions, providing the desired accentuation. By the provision of the adjusting nut 23 and the adjusting screw 26, I am able to regulate the valve opening and the pressure on the valve entirely from the outside of the bellows 13 and without disturbing any of the parts of the mechanism.

Having thus described my invention, what

I claim as new and desire to secure by Letters Patent is:

An expression device for automatic musical instruments comprising a wind trunk, a bellows connected by a passage through one wall thereof to said wind trunk and otherwise closed, a valve in said bellows effective to close said passage upon sudden decrease in pressure in said wind trunk, a threaded plunger slidable transversely in the wall of said bellows and engaging an extension of said valve, a nut on said plunger limiting inward movement thereof, a spring fixed to the outer side of said wall, engaging said nut, and effective to hold said valve normally open, an adjustable stop for limiting the inward movement of the valve, and an adjusting screw engaging said spring intermediate its ends for varying the spring pressure on said means.

In testimony whereof I have hereunto set my hand.

JOSEPH FIALA.
